UNITED STATES PATENT OFFICE.

EBENEZER STILLMAN DOUBLEDAY, OF BROOKLYN, NEW YORK.

VENDING-MACHINE.

SPECIFICATION forming part of Letters Patent No. 436,074, dated September 2, 1890.

Application filed October 23, 1889. Serial No. 327,910. (No model.)

To all whom it may concern:

Be it known that I, EBENEZER STILLMAN DOUBLEDAY, a citizen of the United States, residing at Brooklyn, in the county of Kings 5 and State of New York, have invented certain new and useful Improvements in Vending-Machines; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to certain new and useful improvements in vending-machines; and it more particularly relates to that class of vending-machines which are intended for use in vending cigars.

20 The invention has for its object to simplify and cheapen the construction and to render more efficient, durable, and positive in operation this class of machines.

To the above ends, and to such others as 25 the invention may pertain, the same consists in the peculiar combination and novel construction, arrangement, and adaptation of parts, all as more fully hereinafter described, shown in the accompanying drawings, and 30 then specifically defined in the appended claims.

The invention is clearly illustrated in the accompanying drawings, which, with the figures of reference marked thereon, form a part 35 of this specification, like figures of reference indicating like parts throughout the several views, and in which drawings—

Figure 1 is a vertical central longitudinal section through a vending-machine constructed in accordance with my invention. Fig. 2 is a section upon the line 2 2 of Fig. 1. Fig. 3 is a section upon the line 4 4 of Fig. 1. Fig. 4 is a horizontal section upon the line 3 3 of Fig. 1, with parts broken away in order 40 to better illustrate the construction and arrangement of the parts. Fig. 5 is an enlarged detail in perspective of the sliding plate carrying the delivery-chamber, and also showing the locking mechanism. Figs. 6 and 7 are 45 enlarged front and sectional views of the locking mechanism.

Reference now being had to the details of

the drawings, 1 represents the outer casing of the machine, which casing may be of any suitable or desired form, though in the present instance I have shown an upright case having a horizontally extended base portion 2, the top and one side of the casing being hinged at 3, so as to admit of ready access to the interior of the machine when desired.

Secured within the outer case 1 and adjacent to the front wall of the upright portion thereof is a vertical chamber 4 for the reception of a box containing cigars. The movable platform which forms the bottom 5 of the cigar-chamber is provided with a transverse opening 6, adapted to admit of the passage of a single cigar when a reciprocating motion is imparted to the movable platform or bottom 5 of the cigar-chamber, as will hereinafter be 70 described. The rear portion of the stationary bottom 7 is secured at its ends to the inner sides of the case, as shown at 8, and the forward portion is cut away, as shown in Fig. 2, so as to form the open recess 9 for the passage of the vertically-extended ends 10 of the metallic strips 11, as will presently appear.

12 is a block, one portion of which is secured to the under face of the stationary bottom 7, and its free end is extended some distance to the rear of the rear edge of the same, as shown at 13, and is provided with vertical openings 14, and with a central longitudinal guideway 15 for the passage of the sliding plate 16, said plate being provided with openings 17, adapted to register with the openings 14 when the plate has been moved to the proper point.

To the front end of the sliding plate 16 is riveted or otherwise secured an extension 18, 90 and to the upper face of the free end of this extension is secured the rear end of the cigar-delivering chamber 19, the opposite end of which chamber is provided with an operating knob or handle 20. The metallic strip 11 95 is secured at its center to the under face of the delivery-chamber 19 at a point adjacent to the rear end of the chamber, and the said strip is extended transversely across the machine and has its ends bent upwardly within 100 the recess 9, as is best shown in Fig. 2 of the drawings. The upper ends of the vertical extension 10 are pivoted to the outer edges of the reciprocating platform 5, as indicated at

21, and a reciprocating motion is thus imparted to the said platform by the movement of the delivery-chamber, as will be readily understood.

5 The stationary platform 7 is provided with a central opening 22, which opening is of the size and form corresponding with the opening 6 in the reciprocating platform or bottom of the cigar-chamber 4, but extends in a 10 direction at right angles to the direction of the opening.

Pivoted upon a vertical pivot 23, which extends upwardly from the upper face of the stationary platform 7, at a point adjacent to 15 the recess or opening 22, is a rotatable platform 24, which platform is provided with a recess 25. The upper face of the rotatable platform 24 is provided at a point adjacent to 20 its periphery with a vertical crank-pin 26, the upper end of which is loosely retained in a transverse recess or guideway 27, formed in the lower face of the reciprocating platform 5, as is clearly shown in Figs. 3 and 4 of the drawings. It will be seen that the position of 25 the pin 26 is important, as it serves to regulate the traveling distance of the reciprocating platform and also of the delivery-chamber.

By placing the crank-pin at a great distance from the axis of the rotatable platform the 30 reciprocating platform is permitted a greater movement, and the distance of its travel will of course be lessened correspondingly by lessening the distance between the point at which the pin is secured and the axis of the rotatable platform. By moving the position of the 35 crank-pin in either direction upon the arc of a circle having the axis of the rotatable platform as a center the operating parts of the mechanism may be so adjusted as to permit 40 of the delivery of the contents of the delivery-chamber at any point within the circle of rotation.

The regulation of the movable parts of the machine by changing the position of the 45 crank-pin I consider as an important feature of the present invention; and although in the present instance I have shown the pin fixed at a point necessary to secure a delivery of the goods at a point at right angles to the 50 direction of the recess in the reciprocating platform, the delivery could be made as readily at any other point upon the periphery of the rotatable platform by simply changing the position of the crank-pin, as described.

55 The locking and coin-tripping mechanism can be best understood by reference to Figs. 5, 6, and 7 of the drawings. Reference being had to said figures, 28 represents a plate of metal, which is secured to the upper face of 60 the block 12, and forms a bearing for the lower face of the slide 16. The plate 28 has one of its ends extended beyond the rear of the block 12, and the outer edges of this extended portion are bent upwardly to form the 65 vertical ears 29, near the upper edges of which ears are pivoted the ends of the transverse shaft 30.

31 31 are parallel arms of a lever pivoted or fulcrumed at 30 and provided with a vertical extension 33. The arms 31 are each provided 70 at their free ends with downwardly-extended hooks or lugs 32, adapted to engage the openings 17 in the slide 16 and lock the same against movement when the said slide has been moved to the point necessary to cause such 75 engagement of the hooks. The vertical extension 33 of the lever extends downwardly from the shaft or fulcrum 30 and terminates at a point adjacent to the upper face of the slide 16, which is directly above the opening 80 34 in the said slide when the parts are closed or locked, as shown in Fig. 5.

Secured to the ears 29, at a point adjacent to and in advance of the shaft 30, is the plate 35, the lower portion of which plate is cut away in the center to form the opening 36. To the rear face of the plate 35 is secured the lower end of the coinway 37, which leads from the slit or opening 38, formed in the upper front face of the outer case of the machine. 90

39 is a strip of metal which is secured at a point adjacent to the front edge of the coin-opening 34, where it serves to properly guide the coin, while the downwardly and inwardly extended hooks 40 serve to retain the coin in 95 a substantially vertical position until the time when by the movement of the slide the coin shall have tilted so as to operate upon the locking mechanism.

The operation is as follows: Supposing that 100 the cigar-chamber has been filled with cigars and the parts locked, as shown in Fig. 1. By inserting a nickel (or coin of other denomination, as the case may be,) in the slot 38, the coin will traverse the coinway 37 and will 105 pass through the opening 34 in the sliding plate 16, but will be prevented from falling entirely through the said opening by reason of the engagement of the lower edge of the coin with the projecting lugs 40, and the coin 110 will thus be held in a substantially vertical position, with its upper edge bearing against the lower edge of the plate 33. A slight movement of the operating-handle 20 will move the edge of the coin against the plate with sufficient force to cause the same to move the pivoted lever to cause the hooked ends of the parallel arms 31 to be disengaged from the slide 16, thus unlocking the same and permitting 115 it to be drawn out by means of the handle 20. 120 The tilting of the coin against the fulcrum 60 serves to throw the lower edge of the coin out of its engagement with the hooks, and having been thus released it will drop into the box or drawer 42 provided for that purpose. 125

The movement of the slide by means of the operating-handle will permit the delivery-chamber 19 to be drawn out a sufficient distance to permit the operator to remove the cigar contained therein. The withdrawing 130 of the slide will, by reason of its connection with the rotatable platform, cause the said platform to move forward, thus advancing the position of the aperture therein to the

front of the chamber, where it will register with the corresponding opening in the rotary platform 24, which platform will have, by reason of its connection with the reciprocating platform, been given in the present instance a one-fourth revolution. The return-movement of the slide will again lock the parts, as will be readily understood, while the reciprocating platform will be returned 10 to receive another cigar, and the return of the rotating platform by a one-fourth revolution will cause the opening therein to register with the delivery-chamber, and the cigar carried by the platform will thus be permitted 15 to drop into the delivery-chamber.

In order to provide against the possibility of inserting a coin within the entrance to the coinway when the stock of cigars has been exhausted, I have provided the following simple and efficient mechanism: Pivoted within the bifurcated upper end of the standard 45, the base of which standard is secured to the bottom of the case, is a tilting lever 46, one arm of which lever carries an upward extension 47, which extension is adapted to enter a slot 48 in the bottom of the delivery-chamber when the said chamber is empty. Loosely sleeved upon the opposite end of the lever 46 is one end of the wire 49, which wire extends 20 upward to a point adjacent to and a short distance from the entrance 38 to the coinway 37, where it is bent at right angles to form the horizontal arm 50, having a vertical extension 51, which extension is adapted to pass loosely 25 upward through a hole formed for its reception in the coinway. It will be seen that by this construction the entrance to the coinway will be obstructed by the vertical wire 51 when the delivery-chamber is empty, as when said 30 chamber is empty the lug or projection 47 will enter the slot at the bottom of the chamber by reason of the weight of the wire 49, and the vertical portion 51 at the upper end of the wire will be caused to enter the holes 35 in the coinway, as described. It will also be seen that when a cigar enters the delivery-chamber it will rest upon the upper end of the lug 47, forcing the same downward and thus raising the opposite end of the lever 46 40 and carrying upward the wire 49, thus raising the vertical extension 51 at its upper end from its engagement with the entrance to the coinway and leaving the same open and in 45 readiness to receive a coin.

55 While I have described the machine as used for vending cigars, it is at once evident that such a machine would be equally well adapted for use in vending various articles, and I do not desire to limit myself in this 60 connection to the use of the machine for any particular class of goods. Neither do I purpose to limit myself to the exact construction or arrangement of parts described, as in both of these respects it may be modified without 65 departing from the spirit of my invention.

It will be observed that in describing the construction of the machine that I use the

term "sliding plate;" but it is at once evident that various mechanical equivalents may be substituted therefor, and the present invention fully contemplates the substitution of any and all of these well-known equivalents. 70

Having thus described my invention, what I claim as new, and desire to secure by Letters Patent, is—

75

1. The combination, with the storage-chamber and the rotatable platform beneath the same and each provided with apertures, as described, of a reciprocating delivery-chamber beneath the platform adapted to receive 80 an article from the aperture in the platform, substantially as described.

2. The combination, with the apertured bottom of the storage-chamber, the rotatable platform apertured as described, of a reciprocating delivery-chamber, and connections, substantially as described, between the delivery-chamber and the bottom of the storage-chamber, whereby the said bottom is reciprocated by the movement of the delivery-chamber, substantially as and for the purpose described. 85 90

3. In a vending-machine, the combination, with the movable platform, which serves also as the bottom of the storage-chamber, of the 95 rotatable platform beneath the same, the reciprocating delivery-chamber, and connections, substantially as described, whereby by the movement of the delivery-chamber motion is imparted to said bottom and platform, substantially as and for the purpose described. 100

4. The combination, with the storage-chamber having an apertured bottom, and the rotatable platform apertured as described, of the reciprocating delivery-chamber beneath 105 the platform, a coinway, and a vertically-movable support beneath the aperture in the delivery-chamber and arranged to close the entrance to the coinway when the supply of articles has become exhausted, substantially 110 as described.

5. The combination, with the delivery pocket or chamber and an apertured movable plate connected therewith, of a transverse shaft above the said plate, the stationary 115 block having aperture, as shown, and the gravity-lever adapted to engage the apertures in the plate and block, substantially as shown and described, and for the purpose specified.

6. The combination, with the movable plate, of the rotating platform having diametrically-disposed aperture, the transverse shaft above the plate, the stationary block, the hooked levers secured to the shaft and adapted to engage holes in the plate, the coin-guide 125 130 at the front of the coin-opening, and a tilting lever, also secured to the shaft and adapted when operated upon by a coin to turn the shaft and release the hooks from their engagement with the plate, substantially as and for the purpose described.

7. In a vending-machine, the pin which operates the revolving switch, and which pin admits of such change in its relative position

- to the axis of the revolving switch as will allow the receipt or delivery of the article to be sold at such various points within the circle of its rotation as may be desired, and by 5 which a greater or less traveling distance for the traveling platform and the external delivery-pocket may be effected, substantially in the manner and for the purpose hereinbefore described.
10. 8. In a vending-machine, the combination of a horizontally-revolving switch with a traveling platform above it, said traveling platform traveling in a line with the external delivery-pocket and operated by it, and with the external delivery-pocket operating beneath the switch in the manner and for the purpose hereinbefore described.
9. In a vending-machine, the slot or tram on the under side of the traveling platform, 20 which by its connection with the pin on the switch operates the switch and its pocket in the manner and for the purpose hereinbefore described.
10. In a vending-machine, the combination 25 of a revolving switch, a traveling platform and its pocket superior to it, an external delivery pocket or drawer beneath it, said drawer and superior traveling platform traveling in a common line, with a stationary platform intermediate, for the purpose and in the manner hereinbefore described.
11. In a vending-machine, the combination 30

of a revolving switch, traveling platform, stationary platform, and delivery-pocket, as described, with the box-holder for the merchandise, the opening in the case for the coin, and the coin passage-way from said opening to the locking device, as described, in the manner and for the purpose hereinbefore described. 35

12. In a vending-machine, a locking device 40 consisting of a slide attached to the external delivery-pocket and operated by it, which has at its opposite end a hook encircling the proper coin, (when in its place within the lock,) and which draws the same forward 45 against the lever when the delivery-pocket is drawn outward, a lever operated by the coin and which releases the slide by raising the hook or other device which otherwise retains the slide, the rests or hooks which support the 50 coin until the upper edge of the coin is drawn forward by the slide, and the fulcrum which when the upper edge of the coin is drawn forward throws its lower edge backward and off its support and allows it to drop into the coin- 55 storage box beneath it, substantially in the manner and for the purpose hereinbefore described.

In testimony whereof I affix my signature in presence of two witnesses.
